UNITED STATES PATENT OFFICE

2,474,305

BEATER ELEMENT FOR PULVERIZING APPARATUS

Ollison Craig, Worcester, Mass., assignor to Riley Stoker Corporation, Worcester, Mass., a corporation of Massachusetts

Application April 6, 1945, Serial No. 586,943

2 Claims. (Cl. 241—195)

1

This invention relates to beater elements for pulverizing apparatus, and more particularly to the construction of an improved beater element adapted to be mounted upon the rotor of a high-speed pulverizer and to break up the incoming coarse material into fine particles.

It is one object of the invention to provide a beater element which is capable of operating in a highly satisfactory manner throughout a long life of useful service.

It is a further object of the invention to provide a beater element so constructed that the wear thereon will take place in a uniform manner.

It is a further object of the invention to provide a beater element so constructed that concentrated wear on the walls of the pulverizing chamber will be avoided.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a vertical section through a pulverizing apparatus having my improved beater elements installed therein, the section being taken on the line 1—1 of Fig. 2;

Fig. 2 is a section taken on the line 2—2 of Fig. 1;

Fig. 3 is an enlargement of a portion of Fig. 1; and

Fig. 4 is a perspective view of one beater element removed from the pulverizer.

The pulverizing apparatus illustrated comprises a hollow casing shaped to provide a pulverizing chamber 10 and a fan chamber 11 connected by a central passage 12 which forms an outlet for the pulverizing chamber. An inlet chute 14 is provided to introduce coarse material into the pulverizing chamber 10 at the side opposite the outlet 12. The fan chamber is of scroll form and provided with a tangential outlet passage 15. A tramp metal pocket 16 is located at the bottom of the pulverizing chamber, this pocket being closed by a removable sliding plate 17. A horizontal shaft 19 extends centrally through the casing and is rotatably supported in suitable bearings 20 located outside the casing. A vertical disk 22 is mounted on the shaft within the pulverizing chamber to divide the said chamber into a crushing zone 23 at the inlet side and a grinding zone 24 at the outlet side, these two zones communicating around the periphery of

the disk. On the inlet side of the disk there are mounted beater elements 26 which will be subsequently described in detail, as they form the subject matter of the present invention. On the outlet side of the disk there are mounted beater elements 27 which cooperate with stationary pegs 28 supported on the casing wall. Rejector blades 30 are mounted on the shaft adjacent to the outlet passage 12, and a fan 31 is mounted on the shaft within the fan chamber 11. The pulverizing chamber 10 is provided with a peripheral liner plate 32. Except for the beater elements 26, the various parts as described so far may be similar to those disclosed in my prior Patent No. 1,714,080 granted May 21, 1929.

5 Referring now to Figs. 3 and 4, it will be seen that each of the beater elements 26 comprises a flat plate 33 shaped as a circular ring sector. These plates are mounted closely adjacent to each other on the peripheral portion of the rotor disk 22, and they provide a covering which protects the disk from wear. On the back of each plate there is provided a cylindrical projection 34 which enters a similarly shaped hole in the disk 22 to locate the plate in its proper position. The 10 plates are formed with countersunk openings 35 to receive the heads of bolts 36 which hold the plates against the rotor disk. On the exposed face of each plate there is provided a flat substantially rectangular blade 38 which lies approximately in a radial plane near one side of the plate. This blade 38 is preferably cast integral with the plate and so shaped and located as to avoid interference with the bolt openings 35.

15 The blade 38 is of appreciable width and extends throughout substantially the entire length of the plate 33 (measured radially) which is considerably greater than the width of the blade, so that the front or advancing face of the blade provides a large area for contact with the material which is to be pulverized.

The coarse material is admitted through the chute 14 to the interior of the circle formed by the revolving blades 38. Because of the direction of the air currents and of the initial velocity of the entering material, the material tends to travel outwardly between the blades and close to the plates 33. This has a decided tendency to concentrate the wear on the blades in the region close to the plates, and to concentrate the wear on the peripheral liner plate 32 in the region located in line with the exposed faces of the plates 33. This wear concentration is undesirable, as it greatly shortens the useful life of the parts. In 20 order to avoid this difficulty, the front face of

each blade 38 is provided with a series of generally parallel ribs 39 which extend across the blade in directions approximately perpendicular to the plate 33, and hence across radial lines. These ribs taper in thickness, with their greatest thickness at their junction with the plate 33. Preferably the inner surface 40 of each rib, i. e. the surface nearest the axis of the machine, is inclined gradually outwardly in a direction away from the plate 33. Consequently this surface 40 lies at an obtuse angle with the plate, and as the material travels outwardly over the front face of the blade these inclined surfaces will deflect the material away from the plate and distribute it substantially uniformly over the blade. As a result, the wear on the blade will be uniform, and the wear on the peripheral liner 32 of the pulverizing chamber will be far less concentrated than with prior constructions, greatly prolonging the life of the parts.

It will now be apparent that in the operation of the machine the coarse material to be pulverized will be supplied to the chute 14 by a suitable feed regulator. From this chute the material will drop into the path of the rapidly revolving blades 38 which will serve as preliminary breaking or crushing elements. The material will travel outwardly over the front faces of these blades and during this travel the ribs 39 will cause the material to bounce or skip along the blades, which will increase the impact effect, produce more effective reduction of the material, and decrease the wear on the blades by erosion. At the same time the inclined inner surfaces 40 of the ribs will deflect the material away from the plates 33 and provide a much more uniform distribution of the wear on the blades. Upon leaving the blades the material will strike the peripheral lining 32 of the pulverizing chamber and then flow around the periphery of the disk 22 under the influence of the air current produced by the blades and by the fan 31. In the pulverizing zone 24 the material will be reduced to a fine powder by the action of the revolving pegs 21 and the stationary pegs 28, whereupon the fine material will escape through the central passage 12 to the fan chamber 14. Coarse particles approaching this passage will be returned by the rejector blades 30 to the pulverizing zone. The fine particles will be discharged from the fan chamber in suspension in the air current through the outlet passage 15.

The beater elements 26 will have a far longer useful life than previously known constructions,

and they will greatly increase the life of the liner plate 32. These beater elements, with the tapered ribs 39, are well adapted for manufacture by casting in accordance with known foundry practice.

Having thus described my invention, what I claim as new and desire to secure by Letters Patent is:

1. A beater element for a pulverizing apparatus comprising a rotor wear plate shaped as a circular ring sector and having openings therein to facilitate its attachment to a rotor disk, a substantially rectangular flat blade integral with the plate and extending in an approximately radial plane from one face of the plate, the length of the blade (measured radially) being considerably greater than its width, and a series of generally parallel ribs extending from the plate and across the front surface of the blade in directions approximately perpendicular to the plate, the ribs having inner surfaces which lie at obtuse angles with the plate.

2. A beater element for a pulverizing apparatus comprising a rotor wear plate, a blade extending from one face of the plate and lying approximately in a radial plane, and a series of ribs extending from the plate and across the front surface of the blade, the ribs tapering in thickness, with their greatest thickness at their junction with the plate, the ribs having inner surfaces which are inclined gradually outwardly in a direction away from the plate.
